UNITED STATES PATENT OFFICE

CHARLES A. FINLEY, OF RUTHERFORD, NEW JERSEY, ASSIGNOR TO BOORUM & PEASE COMPANY, OF BROOKLYN, NEW YORK, A CORPORATION OF NEW YORK

VISIBLE LOOSE LEAF DEVICE

Application filed July 28, 1928. Serial No. 296,017.

This invention relates more particularly to top shields for cards mounted in flat over-lapping relation in a drawer or panel.

An object of this invention is to provide a top shield which will not only serve to cover and to protect the uppermost card in a panel, but which will also exert pressure upon the cards to keep them flat upon the panel regardless of the position in which the panel may be placed.

Another object is to provide a support against which to rest a card when it is desired to write upon its reverse side without removing it from the panel.

15 In the drawings,

Figure 1 is a plan view of a panel equipped with my new top shield and carrying a column of cards.

Figure 2 is a longitudinal cross-section 20 through Figure 1 on the line 2—2.

Figure 3 is a section similar to Figure 2, but showing the shield fully open.

Figure 4 is a similar view showing the shield raised to "dead center".

25 Figure 5 is a cross section on the line 5—5 of Figure 1.

Figures 6 and 7 are plan views of modified forms.

Figure 8 is a longitudinal section on line 30 8—8 of Figure 6.

Figure 9 is a similar section, showing the shield open.

Figure 10 is a longitudinal section on the line 10—10 of Figure 7.

35 I have illustrated my invention applied to a panel 15 having the well-known inwardly facing opposed flanges 16 overlying ears or other supporting members of superposed hinged cards 17. It will be obvious that the

40 invention is equally applicable to other types of filing panels or drawers. It is suitable for use with practically any kind of card or sheet.

In Figures 1 to 5 inclusive the invention is 45 shown embodied in a top shield comprising a plate 18 hinged to the panel by a series of fingers 19 sheared out of the strip of spring-metal 20 which is secured to the panel in any suitable manner as by the rivets 23. As shown 50 in Figs. 1 and 5, the ends of the strip 20 may

be slipped under the flanges 16, and the top bar 24 may be placed over it and all riveted to the panel in one operation.

The plate 18 is perforated near its hinging edge at 21 to receive the ends of the fingers 19, which have open knuckles 22 to grip the portion of the plate bounded by the perforation and the hinging edge, as shown in Figures 3 and 4.

The plate 18 of the shield may be made of any suitable material, but I prefer to make it of sheet-metal such as aluminum. In the form illustrated in Figs. 1 to 5, the hinging edge of the plate rides against the metal floor 25 of the rack of the panel.

If desired a lip 26 may be pressed up from the free edge of the plate to facilitate raising or opening the plate.

When the plate is in closed position, as shown in Figures 1 and 2, the spring fingers 19 cause it to lie as nearly flat against the floor of the panel as intervening cards 17 will allow, thus causing the plate to press upon the cards and keep them substantially flat against the panel (as shown in Fig. 2), regardless of the position in which the panel is placed. When the plate is opened, if it is released in any position between closed (Fig. 2) and dead center (Fig. 4) the spring fingers 19 will instantly pull it back to closed position. It can be left open at dead center. If it is opened beyond dead center, and released, it will immediately assume the fully open position shown in Figure 3. In the fully open position the shield forms a support against which to rest the hinged cards 17, when it is desired to write upon the reverse side 17a of one of them without removing it from the panel. The shield is equally useful for this purpose whether the panel is in upright position or is lying down.

In the modified form shown in Figures 6, 8, and 9 the plate 18a carries hinge knuckles 27, spaced to interfit with hinge knuckles 28 carried by hinge bar 29. The hinge pin 30 is offset in the center where it crosses the aperture 32 between the knuckles 27 as shown in Figure 6 and is firmly secured within said knuckles 27.

A single central spring finger 31 is secured 100

between the top bar 24 and the hinge bar 29, with its free end bearing upon the offset portion of hinge pin. The plate is apertured at 32 to allow for the operation of the spring 5 when the shield is opened and closed.

The modification shown in Figures 7 and 10, differs from that shown in Figures 6, 8 and 9 in the respect that in the former figures the hinge pin is not offset, but an additional pin 33 upon which the free end of the spring 31 bears is secured to the face of the plate below the hinge pin and across the aperture 32.

I claim:

- 15 1. In a visible loose leaf device for superposed sheets, a covering shield for the sheets comprising a swinging plate in combination with a spring adapted to cooperate in providing a hinge for the plate and to hold it 20 in either its open or closed position.
2. In a visible loose leaf device for superposed sheets, a covering shield for the sheets comprising a swinging plate in combination with a spring adapted to cooperate in providing a hinge for the plate and to hold it 25 in either its open or closed position, the plate in its fully open position providing a rest for a sheet while its reverse side is being written upon.
3. In a visible loose leaf device for superposed sheets, a covering shield for the sheets comprising a swinging plate perforated near its hinging edge, in combination with a spring strip secured to said device, the spring 35 strip having a series of fingers grasping the plate through the perforations and hinging the plate to the device and holding the plate in either fully open or fully closed position.
4. A visible loose leaf device for superposed sheets, comprising a panel, a covering shield for the sheets and double acting spring hinge means for securing said shield to said panel and adapted to hold the shield in either 40 an open or a closed position.
- 45 5. In a visible loose leaf device for superposed sheets, a covering shield for the sheets comprising a plate having an aperture in its hinged edge, in combination with means secured to said plate and crossing the aperture 50 adjacent and substantially parallel to the hinge of the plate, and a spring pressing on said means adapted to hold the plate in either an open or a closed position.

In testimony whereof I have signed my name to this specification.

CHARLES A. FINLEY.
